(57) **CLAIM**

The ornamental design for a case, as shown and described.

DESCRIPTION

FIG. 1 is a front, right side, and top perspective view of a case of our design;

FIG. 2 is a front, left side, and bottom perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The claim is directed to shaded surfaces only. The dash-dash broken lines illustrate portions of the case that form no part of the claimed design; all other unshaded surfaces, including those between solid and broken lines, form no part thereof.
